UNITED STATES PATENT OFFICE.

DANIEL G. CORBIN, OF LOVETTSVILLE, VIRGINIA.

DESIGN FOR A BED-SLAT HOLDER.

SPECIFICATION forming part of Design No. 27,213, dated June 15, 1897.

Application filed April 29, 1897. Serial No. 634,483. Term of patent 14 years.

To all whom it may concern:

Be it known that I, DANIEL G. CORBIN, a citizen of the United States, residing at Lovettsville, in the county of Loudoun and State of Virginia, have invented and produced a certain new and original Design for Bed-Slat Holders; and I do declare the following to be a full, clear, and exact description of the invention, such as will enable others skilled in the art to which it appertains to make and use the same.

My invention has relation to a new and original design for bed-slat supports adapted to be secured to the ends of a bed-slat and be connected with a bracket or keeper secured to the inner side of the bed-rail; and it consists of a support of the configuration shown in the accompanying drawing, in which I have represented my invention in perspective.

The leading features of the design consist in the ornamental base-plate 1, having projecting upwardly therefrom a post 2, having a straight front edge 3 and a curved rear edge 4, rounded transversely, and a rectangular cross-head 5, projecting laterally from the upper end of the post and formed with a thin rectangular neck 6, all of which parts are cast integral.

Having thus described my design, what I claim is—

The design for a bed-slat support, as herein shown and described.

In testimony whereof I hereunto affix my signature in presence of two witnesses.

DANIEL G. CORBIN.
